UNITED STATES PATENT OFFICE

166,250

BOTTLE

Elsie G. Ferris, Alpena, Mich.

Application November 5, 1951, Serial No. 17,288

Term of patent 14 years

(Cl. D58—8)

To all whom it may concern:

Be it known that I, Elsie G. Ferris, a citizen of the United States, residing at Alpena, in the county of Alpena and State of Michigan, have invented a new, original, and ornamental Design for a Bottle, of which the following is a specification, reference being had to the accompanying drawing, forming part thereof.

Figure 1 is a side elevational view of a bottle, showing my new design;

Figure 2 is a front view thereof, and
Figure 3 is a top plan view of the same.

I claim:

The ornamental design for a bottle, as shown.

ELsie G. FERRIS.
